C. Johnson,

UNITED STATES PATENT OFFICE.

HOWARD A. JOHNSON, OF NORFOLK, VIRGINIA.

MULTIPLE SLIDING DOOR FOR USE IN AIRPLANE-HANGARS OR OTHER LARGE OPENINGS.

1,352,606.

Specification of Letters Patent. Patented Sept. 14, 1920.

Application filed July 11, 1919. Serial No. 310,000.

To all whom it may concern:

Be it known that I, HOWARD A. JOHNSON, a citizen of the United States, and residing at Norfolk, Norfolk County, State of Virginia, have invented certain new and useful Improvements in Multiple Sliding Doors for Use in Airplane-Hangars or other Large Openings, of which the following is a specification.

0 The present invention relates to sliding doors for large openings and more particularly to such doors for aircraft hangars.

The opening in a hangar for the passage of airplanes is necessarily of large dimensions, and the problem of providing a suitable door for such an opening presents many difficulties. The door being of large dimensions is very heavy and consequently requires considerable power to open and close the same.

The principal objects of the present invention are to provide a suitable door which may be opened and closed by power means; to provide such a door which is supported independently of the building so that the weight of the door does not stress any of the members of the roof of the building, for example; to provide a door which when opened may be stored in a position parallel with the side of the building; to provide a simple and dependable power mechanism for opening and closing the door; and generally to improve the structure of this class of doors. Other objects and features of 35 novelty will be apparent from the description taken in connection with the drawings in which:

Figure 1 is a horizontal sectional view in outlines through a hangar illustrating the arrangement of the doors showing one door open and the other closed;

Fig. 2 is a front elevation to a larger scale of a door constructed in accordance with the present invention;

45 Fig. 3 is a horizontal sectional view of a hangar equipped with doors in accordance with this invention;

Fig. 4 is a sectional view taken substantially on the line 4-4 of Fig. 2;

50 Fig. 5 is an elevation of the two small sections of the door as viewed from the inside thereof;

Fig. 6 is a top plan view of the sections of the door shown in Fig. 5;

Fig. 7 is a sectional view taken substantially on the line 7-7 of Fig. 3, the door having been opened substantially to this point;

Fig. 8 is a side elevation of the truck and cable gripping mechanism shown in Fig. 7;

Fig. 9 is a sectional view of the arcuate section of the track taken substantially on the line 9-9 of Fig. 3;

Fig. 10 is a sectional view taken substantially on the line 10-10 of Fig. 2 illustrating the structure for guiding the top of the door;

Fig. 11 is an elevation of the parts shown in Fig. 10;

Fig. 12 is a view of a detail showing in elevation one of the door supporting trucks and its connection with the bottom hinge between a pair of the door sections;

Fig. 13 is a sectional view taken on the line 13-13 of Fig. 12;

75 Figs. 14 and 15 are sectional views similar to Fig. 1 illustrating modified arrangements;

Figs. 16 and 17 are plan views illustrating a device for automatically swinging 80 the free end section of the door around on its pivot to a position against the adjoining section; Fig. 16 illustrating the positions of the parts before the section is swung around, and Fig. 17 afterward;

85 Fig. 18 is a sectional view taken substantially on the line 18-18 of Fig. 17;

Fig. 19 is a sectional view taken substantially on the line 19-19 of Fig. 17; and

90 Fig. 20 is an elevation in detail, of a portion of the track.

Referring to Fig. 1 it will be seen that the invention is shown in connection with a hangar 20 having openings 21 and 22 in

its opposite sides. In order to allow the 95 passage of an airplane these openings are necessarily of large size. For example, the

openings might be 105 feet long by 26 feet high, although the invention of course is not limited to doors of any particular dimensions.

Furthermore, although a building having openings at its opposite sides is illustrated, it is obvious that the invention is equally applicable to a hangar having a

single opening only. As shown in Fig. 1 the opening 21 is closed by a door D and the opening 22 is adapted to be closed by a door D', this latter door being shown in 5 open position and disposed in a position parallel with the side of the hangar.

According to the present invention each 10 of the doors is made up of a plurality of sections hinged together to swing about vertical axes, and these doors are supported on tracks below the same so that they may be rolled into open or closed positions.

As the two doors and the means for supporting and operating the same are duplicates, it will be sufficient to describe one 15 of the constructions only. Referring to Figs. 1 and 3 it will be seen that the track at the bottom of the door comprises a straight section 23 disposed substantially 20 parallel with the length of the opening. The track also includes a section 24 at an angle to the section 23, preferably arranged substantially parallel with one side of the hangar. These two sections of track 23 25 and 24 are connected by an arcuate section 25. Preferably, the sections 23 and 24 are in the form of the usual T-shaped rails while the arcuate section 25 consists of a flat base 26 having an upstanding portion 27 substantially rectangular in cross section. The outer side of the portion 27 is provided with a guide 28 and the base is provided with a guide 29, for a purpose described hereinafter.

30 The door consists of a plurality of like sections 30. In the hangar shown in Fig. 1 the depth of the building is less than the opening of the hangar, and hence in order to store the door at right angles to the 35 door opening the end portion of the door adjacent the arcuate part of the track 25 when the door is closed has two smaller sections 31 and 32, the section 32 being hinged to swing around against the section 31. 40 The door is supported on a plurality of wheeled trucks 33 which run on the tracks, and power means is provided to effect the movement of the door. As shown in Fig. 2 there is no truck under the left hand end 45 of the small section 32, in order to permit the swinging mentioned above. Furthermore, in the present instance when the door is closed the section 32 occupies the position shown at the bottom of Fig. 1, that 50 is, a position in continuation of the track 23 but in front of the curved section 25. Where possible, however, the hangar is 55 preferably designed so that the two smaller sections 31 and 32 are not necessary, this 60 form being described hereinafter and illustrated in Figs. 14 and 15.

For the purpose of operating the door a cable 34 is provided. One end of this cable is secured to a drum 35 carried by the upper structure of the building at the right

hand end of the door, as viewed in Fig. 2. From this drum the cable extends downward to a guide pulley 36 and thence along opposite the track 23 around the arcuate section 25 and a short distance along the 70 section 24 to a guide pulley 37. Preferably this pulley 37 is provided with mechanism 38 for adjusting the position of its bearings so that the tension of the cable may be kept at the proper amount. From 75 the pulley 37 the cable passes to a pulley 39 and thence to a guide pulley 40 which directs the cable to the drum 35, where it is secured to the drum opposite the first mentioned end. Consequently when the 80 drum 35 is rotated one end of the cable is wound up while the other end is simultaneously unwound. Suitable mechanism 41 is provided for operating the drum 35. Preferably an electric motor is used which 85 may be controlled by a switch disposed in the switch box 42 within reach of the operator. For the purpose of guiding the cable around the outer surface of the arcuate section 25 of the track, an endless chain 90 43 is disposed to pass around sprocket wheels 44 at the ends of the curved section 25. One limb of this chain is disposed between the cable and the exterior surface of the track 25, the other limb extending in a 95 substantially straight line between the wheels 44. The guides 28 and 29 on the track section 25, previously mentioned, act to hold the chain in position. Thus, when the cable moves it will bear against the 100 curved limb of the chain and the chain will move therewith, thereby carrying the cable around the curved section 25 of the track without any wear on the cable. In order to operate the door from the cable, a cable 105 gripping device 45 is provided at the right end of the door, as viewed in Fig. 2. The structure of this device is shown more in detail in Figs. 7 and 8. It may comprise a plate 46 secured to the side of the end 110 truck 33 by the bolts 47. An arm 48 is hinged to the plate 46 as at 49 and the cable is cut and the ends secured to the lower end of arm 48 as at 50 and 51. As shown in Fig. 20, the end of the T rails 23 115 and 24 have their webs and lower flanges cut away, as at 23^a for the sprockets 44. The free end of the rail rests on a seat 25^a in the end of the curved track section 25.

120 Preferably the door sections include a frame consisting of vertical channels 52 and 53 connected at their tops by a channel 54. As shown in Fig. 4 the lower ends of the vertical channels are preferably connected by an angle iron 55. The space 125 within the frame is closed in any suitable manner as by the slats 56. As shown in Fig. 5, preferably these slats do not extend continuously throughout the height of the door but are made in sections, the sections 130

being secured in position by the horizontal reinforcing members 57. In order to reinforce the frame, corner plates 58 are provided on the inside of the door and corner plates 59 at the top of the sections on the outside of the door.

The sections 30 are pivotally connected by hinges 60 disposed near the bottom on the inside of the door as shown in Figs. 5, 10 12 and 13. The pivot pins 61 for these hinges also form a pivotal connection between the trucks 33 and the door sections. As shown in Fig. 12 the pin 61 at its lower end is formed with the reduced portion 62 which is secured in the top plate 63 of the truck, its lower end being riveted over as indicated at 64. As shown in Fig. 13 the vertical channels of the door frames are spaced apart a slight distance to permit these sections to swing relative to each other through a small angle so that the flanges of the channels will not interfere. Only a slight relative swinging is necessary to be provided for as the turning occurs only 25 when the door sections are traveling on the curved track 25.

The upper ends of the door sections are connected by the hinge connection 65, pivot pin 66 of which projects above the top of the door and carries roller 67 disposed between the flanges of the channel iron 68 secured to the underside of a girder member 69 of the building. An antifriction ball or roller 70 is disposed in the upper end of the pivot pin 66 to reduce friction in case the pin strikes the web of the channel. The axis of the pivot pin is disposed in alignment with the axis of the pivot pin of the hinge at the bottom of the door connecting the corresponding sections. The channel 68 thus constitutes a guideway for the top of the door and this guideway is arranged parallel with the track at the bottom of the door. It is observed that the entire weight 45 of the door is carried on the tracks and the girder 69 is free from all weight of the door. This is an important feature for the reason that the size of the girder 69 would have to be considerably increased if it carried the 50 very heavy door of the hangar.

To open one of the doors constructed in accordance with this invention, the section 32 at one end thereof is swung around on its hinges 71 to a position flat against the section 31. The switch 42 is then turned to effect rotation of the drum 35 thus operating the cable which through the gripping device will move the door in an opening direction and this motion will continue until the door is disposed on the section 24 of the track in a position parallel with the side of the hangar. One of the doors in this open position is shown at D' in Fig. 1. To close the door the drum 35 is rotated in the opposite direction which through the cable 34

returns the door to its closed position. It will be observed, as the cable gripping device 45 is disposed at the right end of the door as viewed in Fig. 2, the cable does not need to extend along the entire length of 70 the section 24 of the track, thus permitting the guide pulley 37 to be disposed adjacent the end of the curved track 25. Of course this arrangement of the cable and pulleys might be modified but the disposition shown 75 is preferred.

In certain cases it is desirable to provide means for automatically swinging the section 32 on its pivot around against the section 31 of the door, and in Figs. 16 to 19 inclusive a device for accomplishing this purpose is illustrated. As shown in Figs. 5 and 6 the end of the section 32 near the top thereof is provided with a pin 72 offset inwardly and with a roller 73, the latter being provided to guide the end of the section 32 past the columns of the building, such as illustrated at 74. As the door is opened and the section 32 travels along the track 24 at the side of the building, the pin 72 enters a circular cam groove 73 carried by a plate 74 mounted at the free end of an arm 75 pivotally secured by means of a bolt 76 to the top of the top track or channel 68. In order to prevent sagging of this 95 arm 75 a tie rod 77 has one end pivotally secured to the arm adjacent the top of the free end thereof, and the other end of the tie rod is pivotally secured to an eye bolt 78 carried by one of the roof purlins 79. The 100 pivotal connection 78 is disposed vertically above and in alignment with the bolt 76. In order to positively limit the angle through which the arm 75 may swing the stops or abutments 80 and 81 are provided. Further in order to hold the arm 75 against the abutment 80 so that the cam groove or track 73 will be properly positioned for the entrance of the pin 72, a force is applied to 105 the arm to hold it against said stop. As 110 shown for this purpose a weight 82 is secured to a flexible connector 83 which passes around a pulley 84 and is secured to the arm as at 85. The pulley 84 is carried on a bar 86 pivotally supported at 87. Thus 115 the weight 82 acting through the connector 83 tends to hold the arm against the stop 80.

In the operation of this device, when the door is moved in the opening direction, the pin 72 enters the cam groove or track 73, and as the door continues its opening movement said pin travels in said track, the arm 75 simultaneously swinging about its pivot substantially 180° until the door is guided positively and continuously to the position 120 illustrated in Fig. 17. In order that the section 32 of the door will be parallel with the track 24 and thus have the pin 72 in proper position to enter the cam groove 73, spring means such as illustrated at 88 and 130

89, Fig. 5, are associated with the hinges 71, this spring means acting to hold the section 32 in alinement with section 31 of the door.

5 In the form of the invention described above the straight section 23 of the track is not as long as the opening 22 of the door and hence the necessity for providing a means for carrying the cable around the curved 10 section of the track. In Figs. 14 and 15 arrangements are illustrated in which the straight section of the track is somewhat greater than the length of the opening of the door. Thus in Fig. 14 the opening 22^a is closed by the sections 30^a of the door and one section 30^b is on the curved section of the track. As the end of the section 30^b is adjacent the end of the straight section 24 of the track the cable attaching arm 45^a may 20 be disposed at this end, thus avoiding the necessity for guiding the cable around the curved section of the track. Thus a pulley 100 is disposed at the end of the curved section of the track, and the cable 34^a from the 25 motor passes around the guide pulley 101, thence along the side of the track 24 to the pulley 100, thence back to a guide pulley 102 and to the drum of the operating apparatus.

Again, if the opening 22^a of the door is 30 less than the straight section 23 of the track, as described in connection with Fig. 4, the cable may, if desired, be disposed in connection with the section 23 of the track, this arrangement being illustrated in Fig. 15. In 35 said figure the door is shown in open position, the end section 30^b being on the curved section of the track. The cable 34^b for operating the door passes from the hoisting apparatus to a guide pulley 103, thence along 40 the side of the track to a pulley 104 disposed at the end of the straight section 23. From the pulley 104 the cable passes back to 45 a guide 105 and thence to the hoisting apparatus. The cable attaching arm 45^b is secured to the end of the section 30^b of the door.

Although a specific embodiment of the invention has been described in detail it is to be understood that it includes changes 50 and modifications which come within the scope of the appended claims.

Having thus described the invention what is claimed as new and desired to be secured by Letters Patent is:

55 1. A flexible sliding door, comprising sections hinged together vertically, a supporting rail located below the same and upon which the door travels and having a curved portion, guiding means for the top of the door, said rail being located in a depression in the floor of the building to which the door is applied, a flexible cable for operating said door, located in said depression, friction reducing means for guiding said cable along

said rail, and means for operating said cable 65 to open and close said door.

2. A flexible sliding door, comprising a supporting rail having two sections at an angle to each other and a curved connecting portion, a cable, means guiding the cable for movement parallel to the track, including an endless-chain, a part of which is guided parallel to said curved portion of the rail, the cable bearing against the outer side of 75 said part of the chain.

3. A flexible sliding door, comprising a supporting rail having two sections at an angle to each other and a curved connecting portion, a cable, means guiding the cable for movement parallel to the track, including a 80 wheel at each end of the curved portion of the rail, an endless-chain passing around said wheels and arranged to travel on the outside of said curved portion against which the cable bears as it passes said curved portion. 85

4. A flexible sliding door, comprising a supporting rail having two sections at an angle to each other and having a curved connecting portion, a cable, means for guiding the cable for movement parallel to said rail said means comprising a slideable member movable with said cable and located between said cable and the curved portion of said rail and bearing against the latter. 95

5. A flexible sliding door comprising a depressed supporting rail having two sections at an angle to each other and having a curved connecting portion, a movable cable disposed parallel to and along said depressed 100 rail, and friction reducing bearing means for the cable adapted to travel between the cable and the outside of the said curved portion.

6. A flexible sliding door comprising vertically hinged sections, an end section hinged to swing around to a position adjacent its adjoining section, spring means tending to hold said end section in alinement with said door, rolling means supporting said door, 110 and means, acting positively to swing said end section substantially 180° on its hinges, as the door is moved longitudinally.

7. A flexible sliding door comprising a hinged end section adapted to swing about 115 the edge of the adjacent section and a continuous guide acting positively to swing said section substantially 180° on its hinges as the door is opened and closed.

8. A flexible sliding door comprising an 120 end section hinged to swing about the edge of the adjacent section to a position facing the said adjacent section and means acting positively to swing said end section on its hinges substantially 180° as the door is 125 opened and closed, said means including a pin on the end section and a member having a cam groove to receive and guide said pin.

during the swinging movement of said end section.

9. A flexible sliding door comprising an end section hinged to swing about the edge 5 of an adjacent section to a position facing said adjacent section and means acting positively to swing said end section substantially 180° on its hinges as the door is opened and

closed, said means including a pin on the end section, and a pivoted member having a 10 semi-circular cam groove therein adapted to guide the pin during the swinging movement of said end section.

In testimony whereof I affix my signature.

HOWARD A. JOHNSON.
